No. 878,781.

PATENTED FEB. 11, 1908.

E. B. DE LA MATYR.
WINDOW SASH FASTENER.
APPLICATION FILED FEB. 11, 1907.

UNITED STATES PATENT OFFICE.

ELIAS B. DE LA MATYR, OF LOS ANGELES, CALIFORNIA.

WINDOW-SASH FASTENER.

No. 878,781.

Specification of Letters Patent.

Patented Feb. 11, 1908.

Application filed February 11, 1907. Serial No. 356,931.

To all whom it may concern:

Be it known that I, ELIAS B. DE LA MATYR, a citizen of the United States, residing at Los Angeles, in the county of Los Angeles and State of California, have invented a new and useful Window-Sash Fastener, of which the following is a specification.

This invention relates to improvements upon a window fastener heretofore invented by me, and for which I have filed application for Letters-Patent of the United States, Serial Number 353,389, filed the 21st day of January, 1907, also to adapt the fastener to be more readily attachable and detachable so as to be more convenient for use of a traveler who may desire to apply the fastener temporarily to the window of a room which he transitorily occupies.

Objects of this invention are simplification and reduced cost.

The invention may be embodied in numerous forms, and I do not limit the same to specific contrivances.

The accompanying drawings illustrate the invention.

Figure 1 is a view of the invention in one of its forms as applied ready for use. Fig. 2 is a view of another embodiment of the invention. Figs. 3, 4 and 5 show other embodiments of the invention omitting the guard. Fig. 6 is a cross-sectional view of an embodiment of the invention. This view may be regarded as practically a section on line x^6-x^7 , of either Fig. 1 or 2. Fig. 7 is a cross-sectional view which may be regarded as taken on line indicated by x^6-x^7 , of Figs. 1 and 2. The variations in form shown in Figs. 6 and 7 are applicable to the device as illustrated in Figs. 1 and 2. Fig. 8 is a plan 40 of a keeper detached.

1 designates a keeper intermediately bent as at 2 and perforated vertically as at 3, the bend 2 being adapted to fulcrum on the top of the lower sash 4 to which the keeper is to be pivoted by a screw 5 which may be of any desirable form, either provided with a screw-eye 6 or with a slotted head 7.

8 is a loop which engages the top of the lower sash 4, and which is perforated as at 9 to receive the screw 5. It may have a perforated foot 10 through which a fastener as screw 11 may be inserted to secure the loop to the window-sash independently of the fulcrum-screw 5.

55 By perforating the plate vertically as at 3, that is to say, at approximately right angles

to a straight line drawn from end to end of the two limbs of the bent plate, the plate may be fastened by the very simple device shown, so as to effect the locking of the sash and yet be free to yield to the pressure of a thumb or finger on the free end of the plate. By using the screw-eye in combination with such vertically perforated plate, perfect freedom for a tilting movement of the plate for locking and unlocking the sash is secured, together with perfect security against any sliding of the bent plate on top of the sash.

12 is a guard plate which may have a roughened face 13, and may be fastened to the upper sash 14 by screws 15; said plate being seated in said upper sash 14. The sash-engaging portion 16 of the keeper 1 may terminate in a bent portion which may be variously formed, different forms of the same being shown at 17, 18, 19. In Fig. 2 the sash-engaging portion 16 is shown as an unbent end of the keeper 1. In the several views the different forms of keepers are indicated by the character 1, different forms 80 being designated by the addition of an exponent.

The purpose of the loop 8 is to form a positive support for the head of the screw 5 in order that the screw may be tightly screwed down into the window-sash without tightly engaging the keeper. It is necessary that the keeper be free to respond to gravity, and the sash-engaging limb of the same having the portion 16 is of greater weight than the free limb 20, so that gravity normally holds the sash-engaging limb in engagement with the sash, so that as the lower sash lowers or the upper sash rises the limb will rest against said sash but will not impede the movement thereof; but on the reverse movement of either sash which would tend to open the window the friction of the sash on the end of the keeper causes the keeper to wedge tightly against the sash, thus to lock the window 100 against further movement.

The guard plate 12 may be roughened where desired, the purpose of said guard-plate being to protect the upper sash from defacement by the engagement of the keeper. 105 The character of such roughening is immaterial, all that is necessary being that the friction between the plate and the keeper shall be sufficient to prevent the slipping of the one past the other when the tendency of the window is to open.

By this invention in its simplest form, the

traveler is supplied with a fastener consisting of two extremely simple parts which can be most expeditiously applied to and taken from the window with but slight exercise of skill.

It is not necessary to the locking action that the plate be employed, and said plate has been omitted from some of the views. In the simplest form of this invention the head of the screw may be in the form of an eye as shown at 6, thus enabling the fastener to be applied to a window without the use of tools. This simple form adapts the device especially for the use of travelers who may desire to protect themselves against burglars by temporarily applying fasteners to the windows of their temporary apartments.

What I claim is:

1. A window sash fastener comprising a

plate bent intermediately and perforated vertically substantially as set forth at the bend, and a screw extending through the perforation to detachably fasten the plate to the window-sash.

2. A window sash fastener comprising a keeper bent intermediately and perforated vertically at the bend, a perforated loop over the bend, means to fasten the loop to the top of the lower sash, and a screw extending through the perforations of the loop and keeper to seat in the top of the lower sash.

In testimony whereof, I have hereunto set my hand at Los Angeles California this 28th day of January 1907.

ELIAS B. DE LA MATYR.

In presence of—

JAMES P. TOWNSEND,

M. BEULAH TOWNSEND.
